REFRIGERATOR CABINET DOOR COMBINATION

HANDLE AND NAME PLATE SUPPORT

William W. Bell, Jr., Marcellus, N.Y., assignor to Carrier Corporation, Syracuse, N.Y., a corporation of Delaware

Filed Dec. 31, 1958, Ser. No. 784,359

6 Claims. (Cl. 40—10)

This invention relates to cabinets, more particularly to domestic refrigerator and freezer cabinet doors, and means for providing handles and name plates on said doors.

Refrigerator and freezer cabinets are formed in a variety of shapes and sizes. These cabinets generally comprise a rectangular box having one face thereof open to provide access to a refrigerated compartment within the cabinet. A door is mounted over the opening to close same when not in use, and to permit access to the refrigerated compartment when desired. In commercial production of refrigerator and freezer cabinets, two basic types have been evolved. One type of refrigerator and freezer cabinet is provided with a door which in closed position is arranged in a horizontal plane. This is commonly denoted as the chest model. Another conventional cabinet has the door arranged in a vertical plane and is commonly designated as an upright model. Conventional refrigerator cabinets are generally provided with a decorative name plate to identify the manufacturer of the product. Since the door is arranged on the most accessible surface of the refrigerator cabinet, the name plate is generally secured to the door. Additionally a handle is provided to implement movement of the door from a closed to an open position.

As in all manufacturing processes, it would clearly be desirable to employ a single name plate structure, and a single handle structure, on as large a variety of products produced by any given manufacturer as possible. This would thereby minimize the cost of manufacturing, in eliminating the need for distinct parts. Additionally it would be desirable to incorporate as many functions as possible in a single structure.

It is with the above desiderata in mind, that the present means have been evolved, means providing a combination handle and name plate support which permits utilization of the same structure on either a vertically mounted, or horizontally mounted door of a refrigerator cabinet, whereby the same structure may be utilized on either upright or chest type refrigerator cabinets.

It is accordingly a primary object of this invention to provide a combination handle and name plate support for use on a variety of refrigerator cabinets.

Another object of the invention is to provide a combination handle and name plate support which permits orientation of a name plate for maximum visibility regardless of the door in connection with which the handle and name plate support are mounted.

A further object of the invention is to provide a combination handle and name plate support which may be used on a variety of refrigerator cabinets, and in which any selected name plate may be readily mounted.

These and other objects of the invention which will become apparent from the following disclosure and claims are achieved by provision of a combination handle and name plate supporting structure. The name plate support comprises a frame having a fixed retaining lip secured thereto. Opposite to said fixed retaining lip is a removable retaining lip held on the frame by means of a detachable element such as a clip, spring grommet, screws or the like. A handle is secured to the frame in a plane offset therefrom so that upon mounting of the frame on a refrigerator cabinet door, space will be pro-

2

vided between the handle and the door for insertion of the fingers. In use, the combination handle and name plate support is secured to a refrigerator cabinet door so that the handle will be most effective in implementing door opening. Thereafter the selected name plate is arranged in engagement with the fixed retaining lip, and oriented for maximum legibility. The removable retaining lip is then arranged in engagement with the frame and the name plate to secure same in position.

10 The specific structural details of a preferred embodiment of the invention, and their mode of functioning, will be made most manifest and particularly pointed out in clear, concise, and exact terms in conjunction with the accompanying drawings, wherein:

15 FIG. 1 represents a perspective view of an upright refrigerator cabinet having a vertical door provided with the novel combination handle and name plate support; and

20 FIG. 2 is a perspective view of a chest type refrigerator cabinet having a horizontal door provided with the novel combination handle and name plate support; and

25 FIG. 3 is an exploded perspective view of the combination handle and name plate support without the name plate, showing the removable retaining lip in position prior to assembling; and

30 FIG. 4 is an enlarged cross sectional view through the combination handle and name plate support on line 4—4 of FIG. 1; and

35 FIG. 5 is an enlarged cross sectional view through the combination handle and name plate support on line 5—5 of FIG. 4.

Referring now more particularly to the drawings, like numerals and letters in the various figures will be taken to designate like parts. As best seen in FIG. 3, the novel combination handle and name plate supporting member 10 comprises a base frame 11, consisting of an L-shaped wall 14' and two side walls 18, and a handle 12 offset from the plane of said base frame 11.

40 The front wall 14' is provided with a fixed name plate edge retaining lip 14 formed along one side thereof, note FIG. 4. A cross member 15 having a fixed supporting ledge 16 thereon connects the two side walls 18. Formed along the opposite side thereof and extending forwardly from the cross member 15 are two side members 17' defining with the side wall 18 a supporting ledge 17.

45 A removable retaining member 20 having an inverted L-shaped cross section is provided for positioning with arm 21 extending over supporting ledge 16 to provide a removable name plate edge engaging lip and arm 22 serving to provide a guide surface and finishing facade adjacent the side wall of cross member 15. Fastening means in the form of pins 25 are provided on the lower surface of arm 21 of removable engaging member 20, which forms a removable name plate edge engaging lip. These pins 25 are adapted for insertion in spring grommets 26 mounted in appropriate sockets in cross member 15 so as to provide a detachable mounting for retaining member 20. Handle 12 comprises handle arms 30 formed integrally with sides 18 and extending away from the plane of base frame 11. Between the free end of handle arms 30 a handle bar 31 is formed at a spaced distance from the plane along the bottom of the base frame 11.

55 60 65 70 A name plate 35 having dimensions sufficient to extend between walls 18 and beneath engaging fixed retaining lip 14 and arm 21 of removable engaging member 20 is provided. In the instant embodiment of the invention this will be a rectangular name plate which is positioned in assembled relationship as viewed in FIGS. 1, 2 and 4 to rest on edge ledges 17, and supporting ledge 16, beneath the fixed engaging lip 14 and the removable retainer 20.

Opposed sides of the rectangular plate 35 are relieved to provide shoulders 35'. When assembled in the manner described the shoulders snugly abut the members 14 and 21. If necessary, arcuate notches, not shown, may be provided in the edges to assure clearance of pins 25.

In use the aforesaid novel combination handle and name plate supporting member 10 may be employed to implement opening of either the vertical door of an upright refrigerator cabinet or the horizontal door of the chest type refrigerator cabinet.

Where utilized to provide a handle and name plate support on the upright cabinet U as illustrated in FIG. 1, the base plate 11 of the combination member 10 is secured to the door of the cabinet as shown in FIG. 1. It is mounted near the free end of the door remote from the hinge (not seen in the drawing) so as to provide a satisfactory lever arm for opening of the door. Threaded ferrules 40 are provided to receive screws projecting through the door to secure the frame 11 to the door. The handle bar 31 is arranged uppermost with respect to the base frame 11, as viewed in the drawing. Thereafter, name plate 35 oriented for maximum legibility is arranged on edge ledges 17 and supporting ledge 16 beneath fixed engaging lip 14. Upon forcing pins 25 into grommets 26 the removable engaging member 20 will serve to secure the name plate in position.

Where it is desired to provide a handle and name plate on a chest type refrigerator cabinet C as shown in FIG. 2, the combination handle and name plate support 10 is arranged on the front side wall of the chest door as viewed in the drawing with the handle bar 31 arranged beneath base frame 11. Thereafter, as above described, name plate 35 is oriented for maximum legibility on edge ledges 17, supporting ledge 16, beneath engaging lip 14, and removable engaging lip 20 is secured in position with respect to the base frame 11. Under these circumstances the same plate will be rotated through 180° from its position as shown in FIGURE 1.

It will be observed that a unitary structure combining the functions of a handle and name plate support has been provided which may be utilized in combination with either the vertical door of the upright refrigerator cabinet or the horizontal door of the chest type refrigerator cabinet. Regardless of the handle and name plate support orientation, the name plate may be arranged for maximum legibility. This permits fabrication of a single structure and name plate which may be utilized in variety of combinations thus minimizing costs of production.

The above disclosure has been given by way of illustration and elucidation, and not by way of limitation, and it is desired to protect all embodiments of the herein disclosed inventive concept within the scope of the appended claims.

I claim:

1. On a refrigerator cabinet having a door closing off an interior refrigerated compartment, a combination handle and name plate supporting member which may be used on the door either when it is mounted to close off a vertical face of the cabinet or when it is mounted to close off a horizontal face of the cabinet, said combination comprising: a rectangular frame; a fixed retaining lip secured to one side of said frame; a removable retaining lip on the other side of said frame; opposed edge ledges on opposite edges of said frame; flanges upstanding from the remote edges of said edge ledges; handle arms formed integrally

with said flanges and extending away from a plane through the base of said frame; a handle bar between said arms; and a removable name plate in said frame, whereby upon removal of said removable retaining lip said name plate may be positioned for maximum legibility regardless of the orientation of said handle and name plate supporting member.

2. Apparatus as in claim 1 in which said removable retaining lip is L-shaped in cross section with one arm of the L-shaped lip lying over the name plate and the other arm forming a finishing facade on the frame.

3. Apparatus as in claim 2 in which said removable retaining lip is secured to the frame by pins on said lip inserted in spring grommets in said frame.

4. A handle assembly comprising a frame member and a name plate, said frame member having a fixed retaining lip retaining an edge portion of said name plate, said frame member further having a fixed supporting shoulder adjacent another edge portion of said name plate, a removable retaining member having a retaining arm, fastening means serving to align said removable retaining member with said fixed supporting shoulder of said frame member in a position such that said retaining arm overhangs said fixed supporting shoulder to form a second retaining lip, said other edge portion of said name plate being securely held in said frame member by cooperation of said fixed retaining lip and said second retaining lip with said name plate, said frame member further having a handle arm projecting therefrom and a handle rigidly spaced from a plane through the base of said frame so that said name plate may be secured in said frame member in a predetermined desired position depending on the desired orientation of said frame member.

5. A combination door handle and name plate assembly comprising a frame member adapted to contain a rigid name plate having edges, said frame member having a fixed retaining lip to receive and retain an edge portion of said name plate, a fixed supporting shoulder adapted to underlie another edge portion of said name plate, a removable retaining member having a retaining arm thereon adapted to overlie said other edge portion of said name plate and said fixed supporting shoulder thereby forming another retaining lip to hold said name plate securely in a fixed predetermined position, fastening means holding said removable retaining member in position

45 with respect to said frame member and handle means rigidly secured to said frame so that said name plate may be secured in said frame member in a predetermined desired position depending on the desired orientation of said frame member.

6. An assembly as defined in claim 5 wherein said fastening means holding said removable retaining member in position with respect to said frame member comprises a plurality of spaced spring grommets in a fixed position

55 with respect to one of said members and a corresponding plurality of pins secured to the other of said members, said pins being inserted in said spring grommets to hold said name plate in position.

50 6. An assembly as defined in claim 5 wherein said fastening means holding said removable retaining member in position with respect to said frame member comprises a plurality of spaced spring grommets in a fixed position with respect to one of said members and a corresponding plurality of pins secured to the other of said members, said pins being inserted in said spring grommets to hold said name plate in position.

55 6. An assembly as defined in claim 5 wherein said fastening means holding said removable retaining member in position with respect to said frame member comprises a plurality of spaced spring grommets in a fixed position with respect to one of said members and a corresponding plurality of pins secured to the other of said members, said pins being inserted in said spring grommets to hold said name plate in position.
